CONTROL MACHINE PANEL FOR SWITCH
AND SIGNAL CONTROL SYSTEMSJoseph F. Merkel, Rochester, N. Y., assignor to
General Railway Signal Company, Rochester,
N. Y.

Application May 28, 1948, Serial No. 29,704

3 Claims. (Cl. 177—311)

1

This invention relates to control machines for switch and signal control systems, and more particularly pertains to the provision of means for displaying indications on the control panels of such machines.

In switch and signal control systems, it is desirable to display the track layout in miniature on the control panel with suitable indication means for indicating when the various track sections are included in an established route and when the various track sections of such established route become occupied by a train. This is especially true in systems commonly termed entrance-exit systems in which the control panel has entrance and exit buttons disposed on the miniature track diagram at points corresponding to the respective entrance and exit ends of the various routes of the represented track layout. It has thus been proposed for the control panels of such systems that translucent inserts be employed at spaced intervals on the panel to delineate the miniature track diagram, with suitable indication lamps located on the back of the panel adjacent the various inserts for illuminating such inserts in accordance with the condition of the corresponding track sections. One such system has been disclosed for example in the prior patent of T. J. Judge, Pat. No. 2,298,946, dated October 13, 1942.

In view of the above considerations, one object of the present invention is to provide the most advantageous structural means for a control panel of insulating material for illuminating the various translucent inserts forming the miniature diagram. Since various inserts along the miniature trackway belong to different track sections and also represent different positions of the track switches, it is necessary that the inserts be illuminated individually and selectively. For this reason, another object of the present invention is to provide unitary compact and economical light units for the different translucent inserts which light units are easily installed and easily replaced in the event of trouble. However, the translucent inserts relating to the different positions of a track switch are relatively close together making it difficult to provide individual illumination for the inserts for the different position. Thus, a further object of the present invention resides in the provision of a dual light unit adapted for use in connection with the illumination of the translucent inserts for a track switch and which may be used in connection with the inserts for all kinds of track layouts including cross-overs as well as single track switches, and also including double cross-overs.

2

Another object of the present invention is to provide a light unit which is adaptable for the use of standard telephone type panel lamps in such a way as to facilitate their replacement; and to 5 so arrange the structure that the lamps will employ a minimum of space. The present invention contemplates that the light units will be constructed to have contact circuit connections for the lamps which serve both for electrical 10 connections and to hold the lamps in place.

Other objects, purposes and characteristic features of the present invention will be in part obvious from the accompanying drawings and in part pointed out as the description of the invention progresses.

In describing the invention in detail, reference will be made to the accompanying drawings in which corresponding parts are generally identified by corresponding reference characters and 20 in which:

Fig. 1 is a front elevational view of an entrance-exit control panel;

Fig. 2 is a sectional side elevational view of the control panel as viewed along the line 2—2 of Fig. 1;

Fig. 3 is an end view of a dual light unit such as shown in part in Fig. 2;

Fig. 4 is a side sectional view of the light unit shown in Fig. 3 taken on line 4—4 in Fig. 3;

Fig. 5 is a sectional bottom view of the dual light unit taken on lines 5—5 in Fig. 3;

Fig. 6 is a sectional end view with certain parts omitted of the dual light unit as taken on line 6—6 in Fig. 4;

Fig. 7 is a top sectional view of the light unit for a single insert shown in part in Fig. 2, and taken on line 7—7 of Fig. 9;

Fig. 8 is a side sectional view of the light unit for a single insert taken on line 8—8 in Fig. 9;

Fig. 9 is an end view of the light unit for a single insert as viewed from the left in Fig. 8;

Fig. 10 is an end sectional view with certain parts omitted of the light unit for a single insert taken on line 10—10 of Fig. 8;

Fig. 11 is an end view of a translucent insert for the panel;

Fig. 12 is a rear view of the translucent insert for the panel;

Fig. 13 is a side view of an extractor for removing the lamps from the respective light units; and

Fig. 14 is an expanded view of the two normally interlocked separators for the dual light unit of Figs. 3 to 6 inclusive.

With reference to Fig. 1, a control panel P is shown in part including a miniature track

diagram formed by a plurality of translucent inserts 15 which are of the form shown in Figs. 11 and 12. These translucent inserts 15 may be made of any suitable material such as glass, or some semi-transparent moldable material such as Lucite or the like. These translucent inserts 15 are fitted into recesses in the panel P which extend through the thickness of the panel; and are held in place by suitable cement. The panel P is of some suitable electrically insulating material and sufficiently thick to provide for the mounting of the light units as herein described.

The translucent inserts 15 are all of uniform length for convenience in manufacture and assembly, the length being relatively short in order to insure even illumination throughout its length as provided from a single electric lamp. These inserts are located at spaced intervals along the panel to form the miniature track diagram, there being a relatively small space between inserts, but of sufficient length to allow for the attachment of individual light units on the back of the panel for the respective inserts, as will be presently explained. In referring to Fig. 1 it will be noted that each track switch is provided with a translucent insert for its facing point position and two other translucent inserts, one for each trailing unit position. These three translucent inserts may be said to constitute the portions representing a track switch, and when used in combination with other similar arrangements; a cross-over is formed, or double cross-over, and the like as illustrated in Fig. 1.

At the end of the routes illustrated on the control panel P of Fig. 1 are suitable entrance and exit buttons such as 10NB and 10XB, 11NB and 11XB, 12NB and 12XB, 13 NB and 13XB, for example. These control buttons are employed as disclosed in the above mentioned Patent No. 2,298,946 for controlling the switches and signals which results in the establishment of different routes. When a route is established as for example, from entrance button 11NB to exit button 12XB, it is desirable to indicate this fact to the operator which is done by causing the selective illumination of all of the translucent inserts 15 in that route and this illumination is preferably white in color. Then when a train enters such route in response to its establishment and the clearance of a signal governing traffic thereover, such white indication for the several translucent inserts 15 forming that route in miniature is changed to a red indication, indicating that the corresponding route is occupied by a train. Since any route may be formed by several separate track sections having individual track circuits, it is necessary to provide such control as will give the characteristic illumination of only those inserts for the corresponding track section. Also, since some of the inserts are employed in common with several routes whereas others are employed only in a particular route, it should be clearly obvious that individual illumination of the various translucent inserts 15 is essential in order to provide for the many variations in track layouts which are found in actual practice.

With reference to Fig. 2 it will be seen that the single insert light unit 16 is located at the rear of the panel in a position associated with the translucent insert 15 for the facing point position of the track switch; whereas the light unit 17 is located at the back of the panel for the two translucent inserts 15 respectively associated with the opposite trailing positions of the track switch. For this reason the latter light unit is

termed a dual unit since it provides illumination for two translucent inserts.

The dual light unit 17 of Fig. 2 is shown by an end view in Fig. 3 and a side cross-section in Fig. 4 and a bottom cross-section in Fig. 5. From these figures it will be seen that this light unit 17 has a threaded circular portion 17a at one end whereas the other end 17b is somewhat a square with rounded corners as can perhaps be best seen by the sectional view of Fig. 6. The back of the panel surrounding the two inserts for the trailing positions of the switch is recessed around these two inserts and threaded so as to receive the light unit 17, as best seen by referring to Fig. 2. When 15 the light unit is properly positioned, it may be locked in place by a drop of suitable cement or, where space permits, a suitable lock nut (not shown) may be used.

The light unit 17 is of course hollow and has a number of holes for receiving prongs on the associated spring contacts and separators which are mounted within the light unit for forming what might be termed lamp cells or spaces for the respective lamps that are placed inside the light unit. Since each insert must be selectively illuminated by two different colors, then it means that four lamps L must be mounted within the dual light units 17. Two contact springs 18 are therefore mounted at each side of the light unit 25 by having one end 18a bent in the shape of a hook as viewed in Fig. 4 and passed through a hole such as hole 19 of Fig. 4 with its opposite end 18b looped over the outer end of the light unit in a position provided by a recess as indicated in Fig. 4 at 30 the point 19a for the contact 18.

The inside of the light unit is molded to include two oppositely disposed grooved bosses 20 as seen in Fig. 6 so that a flat piece of opaque insulating material 21 can be slid into the light unit 40 to separate the inner portion of the light unit 17 into two parts. This separator 21 extends throughout the length of the light unit and is flush with both ends which is especially desirable at the end 17a of the light unit threaded into the panel P since the light unit 17 is so turned that this separator 21 determines the particular pairs of lights L which are assigned to the two different inserts 15 for the different trailing positions of the switch with which such inserts are associated.

50 By referring to Fig. 14, it will be seen that this opaque insulated separator 21 is grooved as at 41 and slotted longitudinally as at 42 for a suitable distance to interlock with a metal separator 22 having a longitudinal slot 43 therein. 55 During assembly, the metal separator 22 is slightly bent longitudinally on a line with the slot 43 and inserted into the light unit 17 and when it is at a proper position such as shown in Fig. 5 the opposite halves of the metal separator 22 are 60 straightened so that the extending prongs 22a take positions in the holes 22b in the sides of the light unit as viewed in Fig. 6. The opaque insulated separator 21 is then slid into place as 65 previously described, the slot 42 and groove 41 fitting into the slot 43 in the metal separator 22, as seen in Figs. 5 and 6. In this way, the metal separator 22 is positively held in position and when the complete unit 17 is screwed into the recess in the panel P, the insulating separator 21 70 is also prevented from longitudinal sliding movement.

However, it should be noted that the insulating separator 21 is provided with a diagonal slot 44 at one end which permits the insertion of a colored filter 23 on a diagonal with respect to the

respective lamps L. This filter can be inserted by partly removing the insulating separator 21, placing the filter 23 in the slot 44 and sliding the separator 21 back into the grooved bosses 20 in the light unit, the metal separator 22 having already been positioned as above described. A small spring 26 as seen in Fig. 3 and Fig. 4 is inserted just prior to the final sliding movement of the insulating separator 21 so as to assure that the colored filter 23 will rest tightly against the metal separator 22 along the center of the light unit as viewed in Fig. 4 at the point 25.

In this connection it will be noted that the color filter 23 provides a limit for the lamps L as they are inserted into the lamp cells or spaces provided by the two separators, but the other two lamps L are provided a limit by reason of a short wire or rod 26 extending in front of them and mounted through a hole in the insulated separator 21 as viewed in Figs. 3 and 4. The lamps L such as lamp L are inserted into their respective spaces and held in position by the contact springs 18. The complete unit can then be mounted to the panel and its various wire connections made to the extending terminals of the contact springs 18 and the metal separator 22. Obviously, the various wires making up the necessary circuit connections would make it unhandy to remove the lamps when once installed, but the extractor 27 shown in Fig. 13 is provided with a hollow slotted portion 29 which may be fitted over the end of any one of the lamps L providing sufficient tension to grip the lamp and withdraw it from its space in its light unit. The respective lamps can be easily inserted without use of the extractor.

Referring to Fig. 2, it will be noted that the light unit 16 (Figs. 7 to 10 inc.) for a single translucent insert 15 similarly has a circular threaded portion 16a which is adapted to enter a threaded recess in the panel P surrounding the insert 15. This circular threaded portion is an integral part of the complete light unit which is molded of suitable insulating material so that its lamp-holding portion 16b is oval-shaped as shown by dotted lines in Fig. 9 and illustrated by the cross-sectional view of Fig. 10. The hollow barrel has similar holes 31 at the top and recesses 31a at the bottom for receiving the hooked ends 30a of the contact springs 30 which are provided with loops 30b at the other end to enter the recesses 31a in the outer ends of the light unit.

As viewed in Fig. 7 which is a top sectional view, it will be noted that there are four holes 32b; two on each side of the barrel of the light unit. Two metal pieces 32 of the same shape and each having two prongs 32a on one side are oppositely disposed with respect to each other so that prongs 32a extend in both directions into the holes 32b as viewed in the assembled position in Fig. 7. After these two pieces 32 are inserted into the inside of the light unit barrel on oblique planes with respect to each other and then brought together, the outer ends 32c are soldered together so that an integral separator is thus produced within the mid portion of the light unit barrel. This sweating or soldering together of the two pieces begins at about where they leave the barrel and includes the entire extending portions 32c which also serve as terminals for connecting wires. In this way the separator is held in position and prepared for circuit connections.

In the circular threaded end 16a of the light

unit 16 two semi-circular pieces of glass or other suitable material 33, suitably colored such as amber and red, are inserted until they rest against the separator portion 32 and the extending circular boss 34 around the inner portion of the light unit. A circular recess 35 is provided around the inner surface of this circular portion just in advance of the light filters 33 so that a split metal ring 36 may be inserted into the circular portion and recede into the recess 35 for holding the light filters 33 in place.

The complete unit is assembled on the panel P and the lamps L inserted in their respective spaces as shown in Figs. 2 and 8. Preferably the unit is turned so that the width of the separator 32 is parallel to the longitudinal axis of the translucent insert 15 as seen in Fig. 2. This provides for equal distribution of light from each of the lamps when they are selectively energized. In this connection it is noted that for this reason it is desirable that the separator 32 does not extend too close to the end of the light unit and thus become so close to the translucent insert 15 as to prevent light transmission to its entire surface through the corresponding color filter 33.

In this same connection, it will be noted that the metal separator unit 22 of the dual light unit 17 is likewise kept short so as to allow for the transmission of light to the entire surface of the inserts 15 from all of the lamps L. It is for this reason that it is necessary to provide the color filter 23 on an oblique angle in the dual unit 17. This is especially true since in the dual unit each lamp L must illuminate its corresponding insert 15 throughout its length past the separator 22 whereas in the single light unit 16 each lamp L need provide light past the separator 32 only for the width of the corresponding insert 15.

In both light units 16 and 17, it is desirable that the molded material be white in color or if a dark colored material is used that it be painted white on the inside so as to provide as much reflection from the lamps L as possible to give a full and complete illumination of the inserts 15. In this connection, it should be understood that any suitable material may be used to mold the light units so long as it has electrical insulating characteristics. For example, any formaldehyde type plastic, such as phenolic or melamine, may be used, if desired.

It will also be noted that the various holes in the light unit barrels for supporting the contact springs and the separator pieces, provide for convection of air currents allowing the proper cooling effect to take place. This is especially useful since the shape of the units is such as to provide ample air circulation between the units for the adjacent translucent inserts in spite of the fact that the various units are relatively close together.

It is to be understood that various modifications may be made to the organization without in any way detracting from the present invention. For example, if desired, suitable Celluloid strips of white material, or white paint, such as indicated at 38, may be placed on the panel P between successive translucent inserts 15 in order to make the miniature trackway of the diagram continuous throughout. It is also to be understood that the present invention is applicable to an NX system or any other switch and signal control system where miniature track diagrams of the illuminated type are desired, and when applied to any such system will be equally

useful for any track layout encountered in practice. It is believed that the various parts of the present embodiment of the invention are of such a typical nature that those skilled in the art can readily construct more complex diagrams from the simplified showing in this disclosure. Since the present invention relates more particularly to the structure of the indication displaying means for a control panel, no attempt has been made to show how the lamps for the different light units may be controlled. But it should be understood that any suitable control may be employed as desired, one typical control organization being disclosed in the above mentioned patent to Judge, Pat. No. 2,298,946.

Having described and shown a structure for displaying indications along the miniature trackway of a miniature track diagram on a control panel as one specific embodiment of the present invention, it is to be understood that this form is selected to facilitate the disclosure of the present invention rather than to limit the number of forms such invention may assume, and it is to be further understood that various modifications, adaptations and alterations can be applied to the specific form shown to meet the requirements of practice without in any manner departing from the spirit or scope of the invention except as limited by the appended claims.

What I claim is:

1. In a control panel of insulating material for a switch and signal control system having two diverging tracks connected by a track switch represented thereon by at least two translucent inserts mounted in slots in said panel which slots pass through the panel, there being one such insert for each trailing point position of the track switch, a light unit having a circular threaded portion adapted to be received by a threaded recess in the back of said panel surrounding said inserts for both said trailing positions of said switch, said light unit being hollow for receiving a plurality of electric lamps for the selective illumination of each of the inserts, and an opaque separator of insulating material between the lamps for the insert of one trailing point position and the lamps for the insert for the other trailing point position, to thereby form a double lamp unit, a metal separator straddling said opaque separator at right angles thereto and positioned between the lamps in each half of the double lamp unit, and color filter means associated with the lamps for both trailing point positions, whereby the inserts for both positions may be made to appear distinctive depending upon the selective energization of the lamps for that position.

2. In a control panel of insulating material having a substantial thickness, a plurality of translucent inserts mounted in said panel, a double light unit having a circular threaded portion at one end adapted to be received by a shallow threaded recess in the rear of said panel surrounding said translucent inserts, said double light unit being hollow and of such shape as to

be divisible into at least four light cells, an opaque separator and a metal separator straddling one another at right angles to each other and mounted within said light unit case to form said lamp cells, said metal separator having projections on either side which extend into holes in said case to thereby make said separator secure in its mid position within said case, contact springs and lamps mounted longitudinally in each light cell, said contact springs and said metal separator acting both as electrical conductors and as a means of maintaining said lamps in their effective positions, and color filter means associated with the lamps for both trailing point positions, whereby the translucent inserts for both positions may be made to appear distinctive depending upon the selective energization of the lamps for that position.

3. In a control panel, a light unit for securing to the back of the panel for the illumination of a plurality of translucent panel inserts comprising in combination, a circular case having open ends, one end of said case being threaded for attachment of the case within a circular threaded recess in the back of the panel, said case having diametrically disposed bosses with longitudinal slots formed therein, and said case having diametrical openings therein displaced 90° from said bosses, a diametrical metal separator disposed within said case having detents engaging in said openings, said separator having a central longitudinal slot, a diametrical insulating separator disposed within said case and within said slots of said case, said insulating separator passing through said slot of said metal separator, whereby four individual lamp cells are formed for receiving respective lamps longitudinally within said case, and a metal contact strip secured longitudinally in each of said cells within said case, said contact strip being diametrically disposed in that lamp cell with respect to said metal separator so that said metal separator serves as a common electrical connection for all four cells and an independent circuit connection is provided in each cell by said contact strip.
